SLEEVE

Morris Kleiman, Brooklyn, N. Y., assignor to
 Paragon Uniform Corporation, New York, N. Y.,
 a corporation of New York

Application November 7, 1939, Serial No. 303,176

3 Claims. (Cl. 2—270)

My invention relates to a new and improved sleeve.

One of the objects of the invention is to provide a sleeve having an improved cuff construction which is especially adapted for use in women's dresses and other garments, and more particularly maids' uniforms and the like.

Another object of the invention is to provide an extensible cuff, having elastic means which hold the cuff in predetermined normal open shape, so that the improved cuff will fit snugly at the wrist.

Another object is to provide a simple and efficient construction which can be made easily and cheaply.

Other objects of my invention will be set forth in the following description and drawing which illustrate a preferred embodiment, it being understood that the above statement of the objects of my invention is intended to generally explain the same without limiting it in any manner.

Fig. 1 is an elevation of the improved sleeve, the representation of part of the outer cuff having been broken away, in order to illustrate the construction of the sleeve more clearly.

Fig. 2 is a top plan view of Fig. 1.

Fig. 3 is a partially enlarged section on the line 3—3 of Fig. 1.

Fig. 4 is an enlarged section on the line 4 of Fig. 2.

The sleeve 1 is made of any suitable fabric. It is provided with a pleated cuff 2. The cuff of the sleeve is maintained in pleated form by a plurality of elastic yarns 3 which are applied to the inner side of the inner wall of the cuff of the sleeve.

As shown in Fig. 4, the material of the sleeve is bent inwardly at the cuff thereof, so that the cuff of the sleeve has a double wall. The elastic yarns 3 are made of rubber or of covered rubber, of the well-known "Lastex" type. The elastic yarns 3 are held in position at the inner face of the inner wall of the cuff, by means of lines of stitches 4. The loops of these stitches embrace the elastic yarns 3 at spaced intervals, so that the elastic yarns 3 are held tightly in position. The elastic yarns 3 are applied in tensed condition and when the tension on these yarns is released, said yarns 3 contract to form the pleated end-portion or cuff 2 of the sleeve. Said cuff is readily extensible so that it can be slipped upon the wrist of the wearer, and the elastic yarns 3 then hold the cuff firmly in position on the wrist. The stitches 4 may be chain-stitches or lock-stitches. That is, a lock-stitch may be formed

where the elastic yarn is under tension and while the material is unpleated. The loops 4 thus hold the elastic locking yarn 3. As the tension is released, the yarn 3 contracts between the loops 4, in order to form the pleats.

The ornamental outer cuff is made of any suitable material. This outer cuff also has a pleated portion 6 which overlies a part of the pleated portion 2 of the sleeve. The pleated portion 6 of the outer cuff 5 is provided with elastic yarns 7 which correspond to the elastic yarns 3. The elastic yarns 7 are held in position by means of stitches 8, which correspond to the stitches 4. As shown in Fig. 4, the material of the ornamental outer cuff 5 is bent inwardly.

The ornamental outer cuff is detachably connected to the sleeve by means of tacking stitches 9 which are spaced from each other, as shown in Fig. 2. These tacking stitches 9 can be easily removed so as to launder the outer cuff 5. The outer cuff 5 can then be easily connected to the sleeve, by forming tacks or tacking stitches 9.

Since the ornamental outer cuff is connected to the sleeve only at spaced intervals, the sleeve 25 and the outer cuff can readily expand and contract in unison. The sleeve is provided with the usual longitudinal seam, which is not shown in the drawings, as said seam is of conventional construction. The ends of the ornamental outer cuff 5 are separated from each other, as shown 30 in Fig. 2.

The elastic yarns 3 and 7 are very thin and they do not detract from the ornamental appearance of the sleeve and of the outer cuff 5, since they are invisible at the outer surface of the sleeve and at the outer surface of the ornamental cuff.

I have shown a preferred embodiment of my invention, but it is clear that numerous changes and omissions may be made without departing from its spirit.

I claim:

1. A sleeve having a plurality of elastic yarns abutting the inner wall of said sleeve adjacent the free end of said sleeve, said elastic yarns being spaced longitudinally from each other stitches penetrating the material of said sleeve and binding said elastic yarns to the sleeve, the material adjacent the free end of said sleeve being held in normal pleated formation by said elastic yarns, an outer cuff connected to said sleeve at circumferentially spaced points by means of tacks, said outer cuff having elastic means which hold the end-portion thereof in normal pleated formation, said outer cuff being extensible and contractible

in unison with the pleated end-portion of the sleeve.

2. In combination, a sleeve and an outer cuff, said outer cuff being connected to the end-portion of the sleeve at circumferentially spaced points by means of tacks, the end-portion of the outer cuff and the end-portion of the sleeve respectively having elastic means which hold the same in normal pleated formation, said end-ports of the sleeve and of the outer cuff being extensible and contractible in unison.

3. A sleeve having a depending portion disposed inwardly of the sleeve to form a double wall, a plurality of elastic yarns abutting the depending portion of said sleeve adjacent the free end thereof, said elastic yarns being spaced longitudinally from each other, stitches penetrating

the double wall of the sleeve and binding said elastic yarns to the sleeve, the material adjacent the free end portion of said sleeve being held in normal pleated formation by said elastic yarns, 5 an outer cuff having elastic yarns spaced longitudinally from each other, stitches binding said elastic yarns to the cuff, said stitches and yarns of the cuff and sleeve being in substantial alinement, said elastic means of the outer cuff 10 holding the end portions of the cuff in normal pleated formation, said sleeve and cuff being disposed in spaced apart relationship whereby the cuff is extensible and contractible in unison with the end portion of the sleeve, and detachable 15 means for connecting said sleeve and cuff together.

MORRIS KLEIMAN.
